(57) **CLAIM**

The ornamental design for a controller for endoscope, as shown and described.

DESCRIPTION

FIG. 1 is a top, front and side perspective view of a controller for endoscope showing an embodiment of my new design;

FIG. 2 is a front elevational view thereof;

FIG. 3 is a top plan view thereof;

FIG. 4 is a left side elevational view thereof; and,

FIG. 5 is a right side elevational view thereof.

The portions of the controller for endoscope in broken lines are shown for illustrative purposes only and form no part of the claimed design.
